UNITED STATES PATENT OFFICE.

ARTHUR N. DAVIS, OF BERLIN, GERMANY.

ARTIFICIAL TOOTH.

1,146,556.

Specification of Letters Patent.

Patented July 13, 1915.

Application filed June 20, 1913. Serial No. 774,762.

To all whom it may concern:

Be it known that I, ARTHUR N. DAVIS, a citizen of the United States of North America, and residing at Berlin, Germany, have 5 invented certain new and useful Improvements in Artificial Teeth, of which the following is a specification.

My invention relates to artificial teeth.

In artificial teeth which are fastened by 10 means of bridges, plates or crowns, it has lately been the custom to employ, instead of the pin-teeth used heretofore, removable teeth having crowns which consist entirely of porcelain and have in their lower side a 15 hole by means of which they can be fastened with cement onto a pin located on the U-shaped bridge clasping the rear portion of the tooth. Even if such teeth have considerably improved the appearance of the 20 wearer's teeth, mainly because the entire crown consists of porcelain and the bridge is located only at the rear or underside thereof and is therefore invisible, these teeth have for that very reason a great disadvantage 25 in that the provision of the hole necessitates the tooth being comparatively deep, i. e., broad, in the direction of the interior of the mouth, so that the wearer of such teeth is not inconsiderably troubled thereby. The provision of the hole has simultaneously the disadvantage that, e. g., in 30 front teeth, which must be made comparatively thin, the resulting wall is very thin and these teeth consequently are often 35 broken. The same defect is attached to the side teeth and to molars, because that thickness of wall which is normally adequate becomes considerably reduced owing to the 40 subsequent grinding which is always required at the site, and, if this wall is accidentally subjected to excessive stresses, breakage of the tooth results. Moreover, when this known 45 form of tooth is mounted on a bridge, the latter also needs to project into the mouth to accommodate the abnormal depth of the tooth. The result is that a deep crevice is formed between the lower surface of the bridge and the upper surface of the wearer's 50 gum, because these two surfaces are inclined to one another at an acute angle. Such a crevice is objectionable because it favors remnants of food being retained in the mouth.

A primary object of my invention is to 55 obviate all these defects, and to this end I arrange that the tooth to be fastened to the

bridge or the like has in its side faces, and preferably also in its lower side, grooves or indentations, into which corresponding lugs on the bridge engage, and thus firmly and quite securely hold the tooth. By arranging that these side grooves or indentations are somewhat inclined to each other, my improved tooth can be readily withdrawn 60 from the bridge, and, if desired, be replaced 65 by a new one.

Owing to my improved tooth being designed as described and in consideration of the defects of the formerly employed fastening holes, the following advantages are 70 obtained:—Firstly, the tooth can have a smaller depth and need have only that depth which the natural tooth at the corresponding part of the set of teeth has or has had. Secondly, my improved artificial 75 tooth simultaneously forms a compact mass which is in no place disproportionately weak and consequently can be subjected to great stresses without breaking or cracking. Thirdly, that subsequent grinding of the 80 tooth which is usually necessary is less likely to detrimentally weaken the tooth as has usually been the case with known teeth which have holes. Fourthly, when my new tooth is mounted on a bridge, a deep crevice 85 such as that referred to above is not formed on the lower side thereof, because the bridge does not project so far inwardly.

Two illustrative embodiments of my invention are represented by way of example 90 in the accompanying drawing, wherein:—

Figure 1 is a side elevation, partly in section, showing a side tooth mounted on a bridge according to my invention; Fig. 2 is a vertical section taken on the line *a—a* in 95 Fig. 1, and Fig. 3 is a horizontal section taken on the line *b—b* in Fig. 1. Fig. 4 is a side elevation partly in section, showing a front tooth mounted according to my invention, and Fig. 5 is a rear elevation of the 100 tooth shown in Fig. 4.

Referring to the drawing, the improved tooth 1, instead of having the hole employed heretofore, has, at least in its side faces, grooves or indentations 6 and may 105 preferably have in its under side an indentation 7. The bridge 4 has corresponding rib-like projections 8 and 9 which fit closely into the grooves or indentations and so securely hold the tooth. In other respects 110 the bridge forms, in a manner known in itself, a U-formed support for the rear and

lower portions of the tooth. As Figs. 2 and 5 show, the side grooves or indentations 6 are somewhat inclined relatively to each other, whereby the tooth on either the upper 5 or lower jaw can be readily withdrawn from the bridge should it need to be replaced. The grooves are arranged and formed in the same way in every case and are independent of the form of the tooth. As Figs. 4 and 5 10 show, these grooves can be arranged without difficulty in the comparatively thin front teeth. In each case the tooth forms a compact body which is at no place disproportionately weak, and consequently is not 15 likely to crack or break when subjected to very severe stresses. Grinding is also quite as little likely to result in the tooth being weakened detrimentally. On the other hand, the new form of the tooth permits a 20 considerable reduction in depth as compared with that of a tooth of the above-mentioned earlier type designed for the same place in the set. Hence it follows that the wall of the bridge can, when required, be made considerably thicker than it would be in earlier 25 teeth, without the wearer feeling that the mouth is unduly filled.

An important improvement has been effected in my new form of tooth in so far 30 as the bridge makes a comparatively large angle with the gum above the jaw, as will be understood from Figs. 1 and 4, and consequently remnants of food cannot lodge in such places to the same extent as in the earlier construction of tooth.

It is obvious that my improved tooth can 35 equally advantageously be either employed as a crown or mounted on a plate. As before stated, therefore, the tooth tapers toward the gums like an inverted cone, the top of said tooth being of greater diameter than the portions below it, and the bottom 40 of the bridge ends above the bottom of the tooth. The back of the tooth, therefore, 45 tapers toward the front of the tooth.

I claim:

1. An artificial tooth having grooves in the sides thereof, said grooves being inclined relatively to one another, said grooves

being inclined inwardly to each other in the 50 direction toward the base of the tooth, said tooth being of a wedge shape narrowest at the root portion thereof.

2. In combination, an artificial tooth having a posterior portion of a wedge shape 55 and tapering and narrowing toward the gum, the back of said tooth tapering downwardly and inwardly toward said gum and a support embracing and gripping said wedge-shaped portion in its lower and posterior portions, said support being connected with adjacent teeth.

3. In combination, an artificial tooth having grooves in its periphery and a support having lugs to engage said grooves, the bottom of said support presenting a large angle to the gums, said tooth tapering downwardly and inwardly toward the base thereof.

4. In combination, an artificial tooth having grooves in the periphery thereof, a wedge-shaped portion behind said grooves and tapering toward the front of said tooth, and a support connected with adjacent teeth for embracing and gripping the lower and 75 posterior portions of said wedge-shaped portion, the bottom of said support presenting a large angle to the gums, said support tapering downwardly toward the front of said tooth.

5. An artificial tooth having grooves in the periphery thereof, a wedge-shaped portion behind said grooves, and tapering downwardly toward the front of said tooth, and a support for embracing and gripping 85 the lower and posterior portions of said wedge-shaped portion, the bottom of said support being above the bottom of said tooth, and presenting a large angle toward the gums, said support tapering toward the 90 front of said tooth.

In testimony that I claim the foregoing as my invention, I have signed my name in presence of two subscribing witnesses.

ARTHUR N. DAVIS.
